OF DELAWARE.

DEVICE FOR DISCHARGING MOLTEN MATERIAL.

Application filed March 15, 1919. Serial No. 282,768.

My present invention relates to means for discharging molten material, and particularly molten glass, and has for its object to improve the means for keeping such material in a proper liquid condition as it passes from the main chamber of the furnace to the point where the material issues from an outlet or nozzle, and also to provide improved means for controlling the discharge and for varying the operation without any interruption of the main operation, and further, to improve the mechanism employed for transferring the molten material issuing from the nozzle, to the mold or like receptacle to which such material is to be delivered. The invention also consists in various other constructions and arrangements of parts, as will appear from the description following hereinafter and from the appended claims.

While in the accompanying drawings I have illustrated the application of my invention to a glass furnace and glass-discharge device suitable for use in conjunction with a machine for blowing articles such as bottles, in molds, it will be understood that this is only a typical example of my invention, and that many of its features are susceptible of a much more general application. Numerous modifications may therefore be made without departing from the spirit of my invention as set forth in the appended claims.

In the drawings, Fig. 1 is a partial vertical section, taken on line 1—1 of Fig. 3, and illustrating a portion of the main glass furnace in connection with my invention; Fig. 2 is a cross section taken on line 2—2 of Fig. 1; Figs. 3 and 4 are horizontal sections, taken on lines 3—3 and 4—4 respectively of Figs. 1 and 2; Fig. 5 is a partial horizontal section taken on line 5—5 of Fig. 1; Fig. 6 is a plan view, with parts in section, of the shut-off mechanism; Fig. 7 is a partial section on line 7—7 of Fig. 6; Fig. 8 is a side elevation, with parts in section, of the mechanism shown in Fig. 6; Fig. 9 is an end elevation, looking in the direction of the arrow 9 in Fig. 8; Fig. 10 is a horizontal section taken on line 10—10 of Fig. 9; Figs. 11 and 12 are detail views of a certain clamp device indicated in Fig. 9, Fig. 11 being taken on line 11—11 of Fig. 12, and Fig. 12 on line 12—12 of Fig. 11; Figs. 13,

14 and 15 illustrate the details of a mechanism for receiving and transferring the molten glass as it issues from the nozzle, Figs. 13 and 14 being a vertical section and a plan view respectively, showing said mechanism in one of its positions with respect to the nozzle; and Fig. 15 being a view similar to Fig. 14, but showing the device in a different position.

The wall of the furnace is indicated at 20, and its main chamber at 20'. This chamber contains glass kept in a state of fusion in any well-known manner, the level of the molten glass being indicated at A. At a suitable point on the outside of said main furnace or main chamber is located the auxiliary tank or furnace, which communicates with the interior of the chamber 20' by a passage 21, the inlet orifice of which I prefer to locate entirely below the glass level A, so that any impurities floating on top of the molten glass may not enter said passage, but remain in the main chamber 20'. The discharge orifice 21' of the passage 21 may have its upper limit coincident with the glass level A. This passage 21 is shown as formed partly in the upper surface of a brick or stone 22 and partly in the lower surface of a superposed brick or stone 23, both of these being fitted into a suitable opening of the furnace wall 20. As indicated in Fig. 3, I prefer to have the passage 21 contracted in width from the main chamber 20' outwardly, throughout the length of said passage, while Fig. 1 shows that the bottom of said passage is inclined upwardly from the inlet to the outlet, and also that the height of said passage is first decreasing from the inlet toward the outlet, for about half the length of the passage, and then uniform or constant at the discharge portion of the passage. In line 90 with the bottom of the passage 21, lies the inclined surface 24' of a U-shaped member 24 located in the auxiliary tank, and said inclined surface leads to the horizontal surface 24'', which, together with a like surface 25' of a U-shaped trough 25, forms the bottom of a channel through which the glass from the channel 21 may reach an inlet notch or opening 26' at the upper portion of an upright receptacle or pot 26, preferably cylindrical in its main portion and contracted conically at the lower end, at which is located the glass outlet or nozzle 26''.

The member 24 is spaced from the pot 26, and each of these parts is formed with an upwardly-open recess in which the trough 25 is seated. The nozzle 26" preferably projects slightly beyond the bottom of the auxiliary tank or auxiliary furnace. The pot 26 is located centrally within the semi-cylindrical upper portion 27 and the cylindrical lower portion 28 of a surrounding wall, 5 forming with said pot an annular chamber 29, provided at its lower portion with two diametrically-opposite inlets 29', preferably tapering inwardly, through which a burning mixture of air and fuel (say, gas) may be injected into said chamber 29. Fuel is introduced through the outer pipes 30, and air through the inner pipes 31, provided with perforated heads 31', such air being under pressure. The upper end of the pot 26 is held in position partly by the trough 25, which braces said pot against the member 24, and partly by a refractory wedge 32 set between a lip 26* on the pot 26 and a projection 33' on a top member 33, which latter extends above the upper edges of the pot 26, trough 25, and member 24, said upper edges being flush with one another and with that of the stone 23. At its lower end, the pot 26 is fitted into, and held by, an annular bottom member 34. The auxiliary tank is preferably encased in sheet metal, a bottom plate 35, apertured for the passage of the nozzle 26", co-operating with a vertical wall or shell 36 cylindrical at its lower portion, while its upper portion is semi-cylindrical in front and formed with two parallel plane members at the rear, as shown in Fig. 3. The rear ends of said parallel members are shown secured to the furnace wall 20. The auxiliary tank is further held in position by straps or braces 37 secured at their ends to the furnace wall 20 and converging therefrom forwardly to engage the curved surface at the upper portion of the shell 36. Preferably, this shell is not in contact with the wall 27, 28, but spaced therefrom by an asbestos layer 38. Between the wall 20 and the lower portion of the shell 36, a horizontal supporting member 39 may be placed under the bottom member 27' of the surrounding wall of the auxiliary tank or furnace, 40.

On the top member 33 are supported three arched transverse members 40 and 41 respectively, bridging a horizontal channel 29" which extends rearwardly from the upper portion of the chamber 29 and communicates with the interior 20' of the main furnace chamber by means of a duct 42. The member 40, adjacent to the wall 20, is preferably in position permanently, but the two outer members 41 are removable, being set loosely on the top member 33 and provided with handles or eyes 41' for lifting them more readily. The member 40 is provided with an opening or notch 40' through 45

which extends the vertically-movable gate 43, lifted and lowered by any suitable mechanism (not shown). This gate does not fill or block the channel 29", so that combustion gases may flow through said channel 70 even when the gate is lowered; but in its lowered position the gate rests on the surface 24' of the member 24, forming a glass-tight joint therewith, and is also borne by the pressure of the glass in the main chamber 20', against the rear surface of the U-shaped trough 25, thereby preventing the glass from the chamber 20' passing into the trough 25 and pot 26. On the outer portion of the top member 33 further rests a transverse or bridging member 44 provided with openings 44' in line with the chamber 29 and with the pot 26 (see Fig. 2), these openings being normally closed by bricks such as 45 which are set on the bridging member 44 loosely, so that they may be moved aside readily to uncover any one of the openings 44', for the purpose of inspecting the chamber 29 and the pot 26, or of cleaning said parts. By removing the arched members 41, I provide a top opening of sufficient size for the passage of the trough 25, so that a new trough may be substituted readily when desired. Similarly, if in addition to the members 41 I remove the member 44, the resulting opening is large enough to allow ready access to, and the insertion and removal of, the pot 26 together with the trough 25. In order to obtain a tight joint between the trough 25 and the member 24 on one hand, and the pot 26 on the other side, I prefer to provide a strip 46 of clay or other luting substance at each of the four vertical edges of said trough, see Fig. 3. 50

Against the outlet of the nozzle 26" is fitted a stationary nozzle plate or nozzle guard 47, provided with a perforation in its center to register with the nozzle outlet when the pot 26 is in position, it being understood that the nozzle is set loosely on said guard. The latter may be secured to a stationary plate 48, fastened to the bottom plate 35, as by screws 49, and formed with parallel guides 48', between which is adapted to reciprocate horizontally the carrier 50 of the knife 51 moving across the perforation or outlet of the nozzle plate 47. The carrier 50 is shown with rollers 50' traveling along tracks 52 fulcrumed on a stationary pivot 52' and pressed upwardly by springs 53, so as to hold the knife 51 against the lower surface of the nozzle plate 47. The knife carrier is connected with a reciprocating rod 54, operated by mechanism described hereinafter, 55.

In order that any glass which enters the chamber 29 through cracks or leaks, may not accumulate in said chamber and clog it, I have provided a glass outlet at the bottom of chamber 29, said outlet consisting of an 130

opening 34' in the bottom plate 34, in registry with an opening 35' in the plate 35, and with a notch or aperture 48" in the plate 48.

6 The plate 48 may be adjustable for the purpose of bringing the perforation of the nozzle plate 47 into perfect registry with the nozzle outlet, as by making the holes 48" through which the screws 49 pass, elongated 10 in one direction.

The rod 54, which is guided in a sleeve or bearing 48a on the plate 48, carries at one end a longitudinally-adjustable sleeve 55 with a transverse pivot pin 55' for links 56 15 the other ends of which are connected pivotally at 56' with an arm 57 mounted loosely on a shaft 58 journaled in stationary bearings, such as 59, 59', and 59''. The arm 57 has a segmental guide plate 57' with an 20 opening 57'' adapted to receive the end of a coupling pin 60 mounted to slide in a sleeve 61' formed on an arm 61 secured to the shaft 58 rigidly. The pin 60 has a head 60' for pulling it out of the opening 57'', a coiled 25 spring 62 normally keeping said pin in said opening, so as to couple the arms 57, 61. When the pin has been withdrawn from the 30 coupling position, it may be held in this uncoupled position by giving it a slight turn; this will bring against the outer end of the 35 sleeve 61', a transverse pin 60'' carried by the pin 60 and normally extending through slots 61'' extending lengthwise of the sleeve 61. At another point, say between the 40 bearings 59' and 59'', the shaft 58 carries rigidly a crank arm 63, formed with a projection 63' adapted for sliding contact with a stationary guide 64' on a base 64. The arm 63, near its free end, carries a roller 65 45 adapted to be engaged and operated by cam portions (more fully described hereinafter) on two cam disks 66 and 67 concentric with a shaft 68 journaled in stationary bearings 69, 69'. The cam disk 66 is rigidly secured 50 to the shaft 68, as by means of a nut 70 screwing on a threaded portion of the shaft and pressing a toothed surface of the disk into engagement with a correspondingly-toothed surface of a holding member 71 55 keyed to the shaft. Likewise rigid upon the shaft 68 is a pinion 72, in mesh with a spur gear 73 mounted to turn about an axis 73' on two arms 74, 75 which are normally stationary, but mounted loosely on the shaft 68, and capable of adjustment about the axis of said shaft, as will be set forth presently. The two arms 74, 75 are connected rigidly, as by a bolt 75', so as to compel them to move in unison, although the pin or pivot 60 73' might suffice for making this connection. Rigidly connected with the spur gear 73 is a spur pinion 76, in mesh with a spur gear 77 mounted loosely on the shaft 68. The gear 77 is further in mesh with a spur 65 pinion 78 secured rigidly to a shaft 79 jour-

naled in a bracket 80 extending from the base 64. On this shaft 79 is also secured rigidly a spur gear 81, meshing with a spur pinion 82 which is mounted loosely on the shaft 68, and is rigidly connected with the 70 cam disk 67. On an extension 80' of the bracket 80 is mounted pivotally, at 83', a sleeve 83 in which a shaft 84 is mounted in such a manner as to allow the shaft to turn, while preventing its longitudinal movement. 75 At one end, said shaft is connected with any suitable mechanism for operating it, and for the sake of simplicity, a hand-wheel 84' has been shown as secured rigidly to said end of the shaft 84. The other end of the shaft is 80 screw-threaded, and extends through an internally-threaded sleeve 85, mounted to swing about the axis 73', that is to say, said sleeve is loose both with respect to the gears 73, 76 and with respect to the arms 74, 75. 85 The ratio between the diameters of the gears is such that, normally, the two disks 66, 67, while one of them is not secured to the shaft 68 rigidly, will both rotate in unison with said shaft, as if they were both rigid therewith. Thus, as shown, the ratio between the diameters of the gears 72, 73, is the same as that between the gears 78, 77, so that the gear 77, while loose on the shaft 68, will normally rotate as if it were rigid thereon. 90 Similarly, the ratio between the diameters of the gears 77, 78 is the same as that between the diameters of the gears 81, 85, so that the gears 77 and 85 will have the same angular 95 velocity, thus causing the gear 85, under normal conditions, to rotate as if it were rigidly secured to the shaft 68. Of course, other connections might be devised for causing the two cam disks 66, 67 to rotate in unison normally while allowing one of these disks (in 100 this case the disk 67) to be adjusted circumferentially in relation to the other disk, without interrupting the driving connection.

In the particular example illustrated, the loose disk 67 is held against movement 110 lengthwise of the shaft 68, by being fitted between the pinion 82 and a collar 86, held to turn with said shaft, as by screwing said collar on the shaft, and locking it against rotation by a screw 87 threaded into the 115 collar and pressing inwardly against a clamping member 88, preferably threaded to fit said shaft.

The shaft 68 is driven in any suitable manner, say by means of a pinion 89 secured to said shaft rigidly and meshing with a crown gear 90 on a rotary member 91, which may be a permanently-rotating part of the bottle-making machine the molds of which receive the molten material discharged from the nozzle 26'' and cut off by the knife 51. 120

The disk 66 has a cam 66' which by acting on the roller 65 swings the arm 63 and the shaft 58 in such a direction as to 125

carry the knife 51 to the position in which it closes the outlet of the nozzle 26". Similarly, the disk 67 is made with a cam or incline 67' adapted to engage the roller 65 5 on the other side and thus rock the shaft 58 in the opposite direction to bring the knife 51 to the position in which it clears the nozzle outlet and allows the molten glass to issue therefrom. The action of the two 10 cams 66', 67' is not immediately consecutive, so that after the cam 67' has acted, and before the cam 66' shifts the knife to the closing position, there is a certain interval of time during which the knife remains 15 stationary in the position in which glass may flow from the outlet 26". Obviously, the length of this period or interval may be varied by turning the cam 67' to a different position, circumferentially, relatively to the cam 66'. This is accomplished, even while the machine is in operation, by turning the shaft 84 in one direction or the other, so as to increase or diminish the angular interval between the cams 66', 67', and 20 thus cause the nozzle outlet 26" to remain open a greater or smaller length of time. During such adjustment, the axis 73' of the gears 73, 76 moves in the arc of a circle having its center upon the axis of the shaft 30 68, that is to say, the axis of the gears 72 and 77 which are in mesh with said gears 73 and 76 respectively. Thus the adjustment mentioned does not affect the proper meshing of these gears, and the drive of 35 the cam disk 67 is uninterrupted while the adjustment is being made.

In order to prevent any accidental turning of the adjusting shaft 84, I may connect rigidly with the sleeve 83, as by means 40 of a bar 92, a split collar 93, which by means of a clamping screw 94 and nut 95 may be caused to grasp the shaft 84 so tightly as to prevent its rotation. This is the normal condition of the parts. When 45 it is desired to turn the shaft 84 for adjusting the cam disk 67, the nut 95 is loosened, and after the adjustment has been made, the nut is tightened again to guard against accidental disturbance of the adjustment. This safety or locking device is 50 preferably placed in the neighborhood of the device (such as the hand wheel 84') which serves for operating the adjusting shaft 84; thus both the actuating device and the locking device or safety device will be 55 readily accessible to the operator from the same point.

On the shaft 58 is mounted loosely an arm 60 96 provided with a handle 96' to enable the attendant to swing it to one side or the other. With this arm is connected pivotally at 96", a connecting rod 97, preferably made with joints 97' enabling it to be lengthened or shortened. The arm 96 is held against 65 movement lengthwise of the shaft 58, on one

side by a collar 98 secured to said shaft, and on the other side by a stationary plate 99 which may be secured to one of the bearings, say 59. The plate 99 carries two stops 100 for limiting the rocking movement of the 70 arm 96, and preferably adjustable toward and from each other so that the extent of the rocking movement may be varied. The other end of the extensible rod 97 is connected pivotally at 101' with an arm 101" 75 on a carrier 101, mounted to rock about a vertical axis 102; for instance, this carrier may rock on a stud or axle secured to the bottom of the auxiliary furnace. The carrier 101 is made with two parallel sleeves 101* 80 in which are set, adjustable longitudinally, the ends of rods 103, held in position by set screws 104. The other ends of said rods are secured rigidly to a discharge member 105, say by fitting them tightly into sleeves 85 105' on said member. The discharge member is provided with an inclined channel or trough 105", and to one side thereof is secured rigidly a transfer channel or funnel 106, preferably with a downwardly-contracted passage. I have represented the transfer funnel with a jacket 106' to which a cooling medium, say water, is supplied through an inlet 107. The outlet of the water jacket 106' is connected with a pipe 90 108 extending across the upper portion of the trough 105" and perforated to discharge water into said trough. In one position, as shown in Figs. 2 and 15, the funnel passage 100 is in vertical alignment with the axis B of the nozzle 26", so that (when the knife 51 is retracted) the glass issuing from the nozzle may flow through the funnel passage, say into a mold (not shown) registering at that time with the funnel and located below it. In the other position, see Fig. 14, the funnel 106 is out of registry with the nozzle 26", and the axis B of the latter will be in alignment with the trough 105", so that any glass discharged from the nozzle 26" at this 110 time will flow into the trough and be deflected or conveyed thereby to any suitable place, say into a water pan (not shown).

The operation will be readily understood. The glass in the main chamber 20' is kept in 115 a state of fusion by any well-known or approved means, and always extends into the channel 21, whether the gate 43 be open or closed. When the gate is open, the glass passes on through the trough 25 and notch 26' into the pot 26, filling the same at the time the knife 51 closes the outlet of the nozzle 26". The portion of glass thus retained in the auxiliary tank is strongly heated by the combustion of fuel in the chamber 29. In practice I prefer to use a higher temperature in the auxiliary tank than in the main furnace, so that the molten mass will have 125 a higher degree of fluidity in the auxiliary tank, thereby facilitating the subsequent 130

issue of glass from the nozzle 26" and its passage either through the funnel 106 or the trough 105". The combustion gases from the chamber 29 return into the main chamber 20' of the furnace, through the channel 29', 42. If any combustion gases should blow out at the opening 40' or at leaky points, no serious harm will result; as a matter of fact, however, there is little likelihood of any material escape of combustion gases, for the reason that a strong draft is maintained in the chamber 20', which tends to draw in outside air through any leaks, rather than to allow the combustion gases to escape at such points. When the knife 51 is retracted to clear the nozzle outlet, the glass will flow through the funnel 106 into the mold or other receptacle in position at that time. In its passage through the funnel, the glass will be cooled slightly, but this is incidental, that is, the purpose is to cool the funnel rather than the glass, as a protection against injury to the funnel by the excessive heat. After a suitable interval of time, the knife 51 moves in the opposite direction and cooperates with the stationary plate 47 to cut off the stream of molten glass issuing from the nozzle 26", and in this position the knife forms a valve or shutter closing the nozzle outlet. In the construction indicated, the movements of the knife occur at regular intervals, being timed by the operation of the machine carrying the molds to which the glass is delivered. The time interval between the moment when the knife is retracted to clear the nozzle, and the moment when the knife, in its advancing movement, again closes the outlet, determines the amount of glass delivered at each individual operation, so as to properly fill the individual molds as they are brought successively to the filling position. By means of the adjusting shaft 84, the time of opening the nozzle outlet can be set to occur sooner or later, while the time of closing the outlet remains unaltered. The time interval between these two moments is therefore variable, to adjust the amount of glass delivered at each filling operation, as may be desirable when molds of different capacity are used at different times, or to compensate for greater or smaller viscosity of the glass resulting from differences in its composition.

Preferably, a stationary guard or deflector 109 is provided on one side of the nozzle outlet, to catch and direct into the funnel 106 any glass which the knife 51, in its advancing movement may force aside instead of cutting it off, as intended. It will be understood that the adjustment of the time interval during which the nozzle remains open, may be effected while the machine is in operation, and without stopping the rotation of the shaft 58.

It will be understood that during the normal operation of the machine, the transfer funnel 106 remains in registry with the nozzle outlet, to receive the glass therefrom whenever the knife 51 clears such outlet. Under certain special circumstances, however, it may not be desirable to have the glass flow into the molds or like receptacles, say if the operation is to be stopped temporarily. In such a case, the arm 96 is actuated by the attendant to swing the funnel 106 away from the nozzle axis B, and to bring the trough 105" beneath the outlet of the nozzle, and therefore in position to catch any glass issuing from the outlet. Such glass will be deflected by said trough to a place of disposal, say a water pan (not shown), and the water issuing from the perforations of the pipe 108 will not only preserve the trough from being injured by the heat of the glass, but will also cool the hot glass by direct contact.

Certain features shown in the present application are also disclosed and claimed in Patent No. 1,388,654, granted to me August 23, 1921.

While I have illustrated my invention in the form which I now prefer to use in practice, it will be understood that various modifications may be made without departing from the spirit of my invention as defined in the appended claims:

I claim as my invention:

1. In a device of the character described, a main furnace having an outlet, an auxiliary tank connected with said outlet and provided with a discharge nozzle, means for controlling said nozzle, a heating jacket for said auxiliary tank, a channel connecting the upper portion of said jacket with the interior of the main furnace, above said tank, and a removable cover forming a top wall for said channel.
2. In a device of the character described, a main furnace having an outlet, an auxiliary tank having an inlet at its upper portion and an outlet at its lower portion, means for controlling the outlet of the auxiliary tank, a connecting trough interposed between the outlet of the main furnace and the inlet of the auxiliary tank, a heating jacket surrounding said tank, a channel leading from said jacket into the main furnace and extending over the top of said trough and of said tank, and separate removable covers extending transversely across the top of said channel at different points thereof and normally closing openings through which the trough and the auxiliary tank proper may be removed when such covers have been withdrawn.
3. In a device of the character described, a main furnace having an outlet for molten material, the intake end of said outlet being located entirely below the level of the material in said furnace, an auxiliary tank ar-

- ranged to receive material from said outlet, a heating jacket adjacent to said tank, and a channel separate from said outlet for conducting combustion gases from said jacket 5 into the main furnace above the level of the material therein.
4. In a glass feeding machine, a glass container having a discharge outlet, a shearing device for periodically severing the discharged glass, a cam mechanically connected to operate said shearing device, and means for adjusting the cam while the machine is operating, to change the time during which said shearing device is away from its position directly beneath the outlet, and thereby to change the dimensions of the charges severed.
5. In a glass feeding machine, a glass container having a discharge outlet, a shearing device for periodically severing the discharged glass, and operating means for said shearing device, including a power driven member and a cam mechanically connected to operate said shearing device, said cam 20 being driven by and mounted for angular adjustment relative to said member while the machine is in operation to change the time during which said shearing device is away from its position directly beneath the outlet, and thereby to change the dimensions of the charges severed.
6. In a glass feeding machine, a glass container having a discharge outlet, a glass shearing device, and operating means for said shearing device, including a power shaft, a plurality of cams driven thereby and mechanically connected to operate said shearing device, and means for adjusting one cam relative to another while the machine is operating, to change the time during which said shearing device is away from its position directly beneath the outlet, and thereby to change the dimensions of the charges severed.
7. In a glass feeding machine, a glass container having a discharge outlet, a glass shearing device, and operating means for said shearing device, including a lever and cams for actuating the lever, with means for adjusting said cams relative to each other while the machine is operating to change the time during which said shearing device is away from its position directly beneath the outlet, and thereby to change the dimensions of the charges severed.
8. In combination, a glass container having a discharge outlet, a glass shearing device, an operating member connected with the shearing device and mounted to swing about an axis, and actuating means for said member adjustable to effect a variation in its time of movement to change the time during which said shearing device is away from its position directly beneath the outlet, and thereby to change the dimensions of the charges severed.
9. In combination, a glass container having a discharge outlet, a glass shearing device, a lever for actuating the shearing device, a member for moving the lever in one direction, a second member for moving the lever in an opposite direction, and means for adjusting said members relative to each other, to change the time during which said shearing device is away from its position directly beneath the outlet, and thereby to change the dimensions of the charges severed.
10. In combination, a glass container having a discharge outlet, a glass shearing device, an actuating member engaging the shearing device, and a cam mechanism engaging said actuating member and adapted to move it back and forth to actuate the shearing device; said cam mechanism being adjustable whereby to regulate the amounts of glass severed.
11. In combination, a glass container having a discharge outlet, a glass shearing device, an actuating member engaging the shearing device, and an operating device engaging said actuating member and adjustable to vary its time of movement in one direction without changing the time of movement in the opposite direction.
12. In a glass feeding machine, a glass container having a discharge outlet, a shearing device movable to open and close the outlet, and operating means for said shearing device, including a cam mechanically connected to operate said shearing device, and means for adjusting the cam while the machine is in operation, whereby to vary the time interval between the opening and closing of the outlet.
13. In a glass feeding machine, a glass container having a discharge outlet and a stationary shearing member adjacent to said outlet, a shear member movable in contact with the shearing member to open and close the outlet, operating means for said shear member, including a cam with means for adjusting the cam while the machine is in operation, whereby to vary the time interval between the opening and closing of the outlet, and means for yieldingly holding the shear member in contact with said stationary shearing member.
14. In combination, a ware shaping machine, a glass container having a discharge outlet, a glass shearing device, an actuating member engaging the shearing device, an operating device engaging said actuating member and adjustable to vary its time of operation, to change the time during which said shearing device is away from its position directly beneath the outlet, and thereby to change the dimensions of the charges.

severed, and driving means for said shaping machine and said operating device.

15. In a device of the character described, a container having an outlet, a transfer member having a passage movable into and out of registry with said outlet, a cooling jacket for said transfer member, provided with an inlet and an outlet, a trough connected with said transfer member and arranged to register with the outlet of the container when the passage of the transfer member is out of registry with said outlet, and a perforated tube extending across the upper portion of said trough and connected with the outlet of the jacket to receive cooling fluid therefrom and discharge such fluid into the trough.
16. In combination, a glass container having a discharge outlet, a combined trough and funnel mounted to swing about an axis, means for swinging the trough and funnel to position either one of them in registry with the outlet, and means associated with said swinging means for permitting the trough and funnel to be adjusted radially of said axis.

17. In combination, a glass feeding device comprising a container having a discharge

outlet, a glass shaping machine including a mold support, a combined trough and funnel mounted beneath and supported by said feeding device, said funnel acting to direct glass discharged from the outlet to the molds on said mold support, and means for swinging said trough and funnel to position either of them in registry with the outlet at will.

18. In combination, a glass feeder comprising a container having a discharge outlet, a glass shaping machine, including a mold support, a funnel mounted beneath and supported by said feeder, and adapted for directing glass discharged from the outlet to the molds carried by the support, and means for swinging the funnel into and out of registry with the outlet.

19. In combination, a glass container having a discharge outlet, a funnel, means for swinging the funnel about an axis into and out of registry with the outlet, and means associated with said swinging means for permitting adjustment of the funnel radially of the axis.

In testimony whereof I have signed this specification.

FRANK H. LOBB.
